UNITED STATES PATENT OFFICE

120,476

DESIGN FOR A COMBINED DISPLAY AND DISPENSING CABINET FOR FROZEN FOOD OR THE LIKE

William McKinley Baird, Chicago, Ill.

Application March 11, 1940, Serial No. 90,822

Term of patent 14 years

To all whom it may concern:

Be it known that I, William McKinley Baird, a citizen of the United States of America, residing at Chicago, in the county of Cook and State of Illinois, have invented a new, original, and ornamental Design for a Combined Display and Dispensing Cabinet for Frozen Food or the like, of which the following is a specification, reference being had to the accompanying drawing, forming a part thereof,

Fig. 1 is a front perspective view of a combined display and dispensing cabinet, for frozen food or the like, showing my new design; and Fig. 2 is a rear perspective view thereof.

I claim:

The ornamental design for a combined display and dispensing cabinet for frozen food or the like, substantially as shown.

WILLIAM MCKINLEY BAIRD.
